FIREPLACE CONTAINED AIR CIRCULATING HEATER

Paul H. Sroat, Portland, Oreg., assignor to Heat-Rite Fireplace, Inc., Portland, Oreg., a corporation of Oregon

Application October 19, 1936, Serial No. 106,420

9 Claims. (Cl. 126—121)

The principal object of this invention is to provide a fireplace heater which is self-contained which is susceptible of being easily installed to operate in and to be removed from a standard fireplace opening. My invention is designed to fit substantially all standard size fireplace openings without alteration. To this end, I provide a firebox and an air jacket surrounding said firebox thru which air is drawn by thermal action. 5 A face plate is provided on the forward face of said device which face plate extends laterally from and about the marginal edges of the fireplace opening. Said face plate is sufficiently large that it will overlie the margins of the large 10 standard fireplace openings while the firebox and its surrounding casing or jacket are sufficiently small to be received in the mouth of the small fireplace openings.

A further object of my invention is to provide 20 a heating device of this character which may be supported upon its forward edge with its center of mass arranged rearwardly thereof a substantial distance. The face plate of said device is adapted to bear upon the front of the fireplace about the margins of the fireplace opening and the center of mass of said unit is so placed that it will tend to hold the face plate tightly against the front of said fireplace.

A further object of my invention is to provide 30 the margins of said face plate with a sealing element of such character that it will resiliently accommodate the irregularity to the fronts of fireplaces and will tend to be compressed by the off balance of said center of mass. The placement of mass will hold said face plate with said sealing element extending about the margin thereof against the front of the fireplace so that said face plate is tightly sealed therewith.

A further object of my invention is to provide 40 a fireplace heater of this character with an air vent so disposed as to receive the maximum radiated heat from the firebox and thus produce efficiency in said device. To this end I provide the firebox of said device with two laterally spaced flues and provide the casing or air jacket with a centrally disposed vent extending upwardly between said flues and over the roof of said firebox. Thus the heat is radiated from the sides of the flues and the top of the firebox and heated 45 air is discharged outwardly into a room thru a discharge aperture extending substantially the entire width of said firebox. To induce a more rapid flow of air thru said vents flue gas driven fans are arranged in said two flues and upon a 50 shaft common to said flue fans, is a circulating

fan extending across the air vent and thus a more rapid flow of air thru said vents is induced by said air fan under the driving influence of the fans in the flues.

Further details of my invention are hereinafter described with reference to the accompanying drawings, in which:

Fig. 1 is a sectional view of my self-contained fireplace heater with the center of mass indicated at X and the tipping moment induced by the placement of mass indicated by an arrow;

Fig. 2 is a diagrammatic illustration of my improved fireplace heater illustrating diagrammatically how it will fit into a number of different sizes of fireplace openings;

Fig. 3 is a perspective view of the firebox and the air jacket portions of my device shown separated, portions of the air jacket being shown broken away to disclose details of construction thereof;

Fig. 4 is an elevation of a fireplace with my improved heater shown seated therein;

Fig. 5 is a sectional view therethru taken on the line 5—5 in Fig. 4;

Fig. 6 is a vertical section thru said device taken on the line 6—6 in Fig. 7;

Fig. 7 is a transverse vertical section taken thru said device on the line 7—7 in Fig. 6;

Fig. 7a is a sectional detail of construction; and

Fig. 8 is a horizontal section taken on the line 8—8 in Fig. 6.

My improved fireplace heater comprises a self-contained structure including a firebox member a, an air heating jacket b surrounding, but spaced from said firebox member, and a face plate c. Said face plate extends across the space between the air heating jacket and the firebox member and is sealed tightly about the margin of the open mouth of said firebox member. A sealing ring d is arranged internally of an inturned flange c' on the face plate and between them, a recess is defined for receiving the forward edge of the firebox member, holding said firebox member tightly in place in said face plate. Said ring, flange and the forward edge of the firebox member may be bolted, welded or otherwise secured in place to form a strong rigid structure.

The marginal edges of the air heating jacket also terminate in a laterally projecting flange b', extending outwardly from said jacket and parallel to but spaced from the face plate. The extreme edge of said flange terminates in a laterally projecting marginal flange b2, extending away from said face plate. The face plate also has a marginal flange c2 extending parallel to

but spaced from the marginal flange *b2*. Underlying the space thus formed is a marginal angle element *e* preferably welded or otherwise secured to the face plate and to the flange of the jacket 5 and a square recess is thus formed facing towards the front *f'* of the masonry fireplace *f*. In said recess I preferably provide a resilient sealing element *g* of generous cross section composed preferably of material similar to resilient 10 fabric, corded asbestos or sponge rubber. Normally said sealing element extends outwardly from the recess and is compressed into said recess only under the influence of a substantial pressure.

15 As is indicated in Fig. 1, the center of mass of said self-contained heater is arranged at the point marked *X* in said figure. Thus it extends rearwardly a substantial distance behind the face plate. Said heating device is supported in a fireplace opening *f2* only along the bottom of the face plate. Thus, the off balance mass tends to tip the fireplace heater more deeply into the fireplace opening than to which it is set. It is resisted in said tipping by the engagement of the 20 marginal edges of the face plate *e* with the front of the fireplace. Said tipping effect of the mass of said heater tends to compress the sealing element *g* and said sealing element tends to prevent said heating device from marring the highly 25 finished front of a fireplace. Most fireplace fronts are made of brick or tile and their joints present an uneven surface. The resiliency of the sealing element tends to cause it to move into the irregularities to give the fireplace front the effect 30 of being solidly and exactly fitted along the entire fireplace front. Said sealing element *g* also has its function of sealing to prevent the flue gases from passing upwardly between the face of the fireplace heater and the front of the fireplace 35 place.

40 The firebox member is closed top, bottom, at each side and in the back. The front is open into a room to be heated. I preferably provide a pair of flues *h* extending upwardly from the 45 sides of the interior of the firebox. These are arranged as far towards the side as is possible to leave a space *h2* between them. Lying in said space is a cupped recess *h3* which fits more or less closely about the path described by the tips 50 of the blades of a circulating fan *i* seated therein.

55 The floor *a'* of the firebox member is provided with draft apertures *a2* preferably arranged only along the forward edge thereof. I preferably arrange a grate *j* or fuel container in said firebox with the forward edge just inside said draft apertures. Thus, fuel located in said grate is permitted to burn with the air flowing inwardly thru the mouth of the firebox member and supplemented by the air flowing upwardly thru the said 60 draft apertures *a2* in the floor or the firebox member.

65 Underlying the apertures in the bottom of the firebox is a retractable tray *q* constituting an ash receiver. Said tray is reciprocally mounted between two opposed slides *r*. When the tray is seated tightly against the front of the face plate it effectively prevents air for supporting combustion from flowing upwardly thru the apertures *a2*. If said tray is withdrawn slightly, an auxiliary draft is provided for increasing the flow 70 of air upwardly thru said apertures.

75 In Fig. 5 the flow of flue gases is diagrammatically illustrated. In each of said flues *h* is a fan *k*. Said fans are substantially larger in diameter than the circulating fan *i* located in

the chamber between the air heating jacket and the firebox member. The fans *k* are housed within a rounded portion *h4* in each of the flues. The two flue fans *k* and the circulating fan *i* are carried by a common shaft *l*. The flue fans are 5 positioned and arranged, as is shown in Figure 5, so that the ascending flue gases strike the blades of the fan and tend to rotate them. This gives rotation to the circulating fan *i* to produce forced 10 draft of heated air, as will hereinafter be described.

15 The passageway for air to be heated is located between the exterior of the firebox member *a* and the interior of the air heating jacket *b*. Arranged inwardly of said jacket is a heat reflector *m* of curved shape and preferably having a highly polished surface. I preferably make said heat reflector of stainless steel or similar material and find that said device improves the efficiency of the 20 heater. Said heat reflector extends from adjacent the floor of the air heating jacket up the back thereof and along the roof overlying the firebox, but spaced therefrom. The space *h2* between the flues forms a vent underlying the heat reflector, overlying the top of the firebox, and closed at the sides by the opposed faces of the flues. I have observed that the point of greatest 25 heat is located here and the air flowing across the top of the firebox thru said vent is heated to the greatest degree. To obtain forced draft along 30 said vent, the circulating fan *i* extends across the entire width of said vent but not the height thereof. Said fan serves to increase the quantity and rate of flow of air thru said vent substantially. That is, the rise in heat thru the passageway inside of the jacket due to progressively greater 35 heat in the upper portions of said jacket produces a thermal flow of air which is supplemented by the driven fan.

40 Two intake apertures *n* extend thru the face plate *c* at the sides of the firebox opening. Said apertures preferably are covered by grill work or louvers. The air flowing therethru passes along the side of the firebox within the air heating jacket and then passes inwardly over the back and top 45 of said firebox member thru the vent previously described. A discharge aperture *o* extends substantially across the entire face plate over the firebox opening. As can be seen in Figures 5 and 7 most clearly, the face plate is cupped so 50 as to extend outwardly from its point of joinder with the flange *b* of the jacket. Thus, lying between said face plate and said flange *c* is a marginal auxiliary chamber *p* into which the intake apertures *n* open and from which the discharge apertures permit the heated air to flow.

55 As is diagrammatically illustrated in Figure 2, my improved fireplace heater is adapted to be mounted in fireplace openings differing substantially in width and height. As is shown in dotted lines, said fireplace heater can be arranged in fireplace openings varying in width from *z* to *a2* and in height from *y* to *y2*. This is effected by the relatively large difference in size of the air heating jacket of my device with respect to 60 the marginal dimensions of the face plate thereof. It is usual to have a substantial area about the front of a fireplace below the mantle *f3* thereof and between the sides *f4* thereof. Thus, it is relatively unimportant how far over the marginal 65 edges of the face plate overlies the marginal edges of the fireplace opening because of the fact that my device is arranged with its mass off center. Thus, the marginal edges of the face plate will be held tightly in place independent 70 of the fireplace opening. This is effected by the 75

of auxiliary securing devices. The sealing element *g* extending about the marginal edges of the face plate accommodates slight irregularities in the fireplace front and the compression is 5 dependent upon the force applied.

My improved fireplace heater can be arranged in a fireplace opening merely by pushing the lower end inwardly until the marginal edges of the face plate engage evenly about the face of the 10 fireplace. Thus, I have provided a heater of the circulating type which can be arranged in the fireplace out of the room proper and which will be capable of producing circulating heat with surprising efficiency. The flues are arranged to 15 align with the chimney *f* of the fireplace *f*.

I claim:

1. A heater adapted to seat in a fireplace opening, comprising a self-contained removable unit including an open mouthed firebox, an air 20 heating jacket surrounding and spaced from said firebox and a face plate extending across the mouth of said casing and seated about the open mouth of said firebox and joining said parts together, the whole of said heater unit lying rearwardly of said face plate, the firebox lying substantially entirely within the firebox opening and the mass of said unit being supported adjacent the plane of said face plate and the center of mass of said unit lying substantially rearwardly 25 of said plane, whereby said disposition of mass exerts a substantial tipping moment about said support to tend to cause said face plate to bear tightly against the front of the fireplace.

2. A heater adapted to seat in a fireplace 30 opening, comprising a self-contained removable unit including an open-mouthed firebox, an air heating jacket surrounding and spaced from said firebox and a face plate extending across the mouth of said casing and seated about the open 35 mouth of said firebox and joining said parts together, the whole of said heater unit lying rearwardly of said face plate, the firebox lying substantially entirely within the firebox opening and the mass of said unit being supported adjacent 40 the plane of said face plate and the center of mass of said unit lying substantially rearwardly of said plane, whereby said disposition of mass exerts a substantial tipping moment about said support to tend to cause said face plate to bear 45 tightly against the front of the fireplace, a sealing member extending about the face plate and adapted to seat against the fireplace front under said tipping force.

3. A heater adapted to seat in a fireplace opening, comprising a self-contained removable unit including an open-mouthed firebox, an air heating jacket surrounding and spaced from said firebox and a face plate extending across the mouth of said casing and seated about the open mouth 50 of said firebox and joining said parts together, the whole of said heater unit lying rearwardly of said face plate, the firebox lying substantially entirely within the firebox opening and the mass of said unit being supported adjacent the plane 55 of said face plate and the center of mass of said unit lying substantially rearwardly of said plane, whereby said disposition of mass exerts a substantial tipping moment about said support to tend to cause said face plate to bear tightly 60 against the front of the fireplace, a resilient sealing member extending about the face plate, and adapted to seat against the fireplace front and to be compressed by said tipping force.

4. A heater adapted to seat in a fireplace opening, comprising a self-contained removable unit

including an open mouthed firebox, an air heating jacket surrounding and spaced from said firebox and a face plate extending across the mouth of said casing and seated about the open mouth of said firebox and joining said parts together, 5 said face plate having an intake aperture and an exhaust aperture overlying the intake aperture, both apertures extending into said jacket, said face plate provided with laterally projecting flange portions adapted to extend beyond the 10 margins of said fireplace opening and to seat against the front of said fireplace, the whole of said heater unit lying rearwardly of said face plate, the firebox lying substantially entirely within the firebox opening and the mass of said 15 unit being supported adjacent the plane of said face plate and the center of mass of said unit lying substantially rearwardly of said plane, whereby said disposition of mass exerts a substantial tipping moment about said support to 20 tend to cause said face plate to bear tightly against the front of the fireplace and a sealing member extending about the face plate and adapted to seat against the fireplace front under said tipping force.

5. In a fireplace of the circulator type, a firebox having a flue extending upwardly, an air heating jacket extending about said firebox including an upwardly projecting vent extending over the top of said firebox and alongside said flue, an intake aperture entering the jacket at the bottom and a discharge aperture communicating with the top thereof, and a curved heat reflector element arranged in said jacket spaced from but facing said firebox, said reflector extending into and overlying said vent.

6. In a fireplace of the circulator type, a firebox having a pair of laterally spaced flues extending upwardly from adjacent the sides of the firebox, an air heating jacket extending about said firebox and over the space between said two flues including an upwardly projecting vent extending over the top of said firebox and between the flues therefor, an intake aperture entering the jacket at the bottom and a discharge aperture communicating with the top thereof.

7. In a fireplace of the circulator type a firebox having a flue extending upwardly, an air heating jacket extending about said firebox including an upwardly projecting vent extending over the top of said firebox and alongside said flue, fan members located upon a common shaft, one extending across said vent and another across said flue, said flue fan positioned to be rotated by the gases passing up said flue and to correspondingly rotate the vent fan to tend to force the movement of air thru the vent, an intake aperture entering the jacket at the bottom and a discharge aperture communicating with the top thereof.

8. In a fireplace of the circulator type a firebox having a pair of laterally spaced flues extending upwardly, an air heating jacket extending about said firebox including an upwardly projecting vent extending over the top of said firebox and between the flues therefor, fan members located upon a common shaft, one extending across said vent and another across each of said flues, said flue fans positioned to be rotated by the gases passing up said flues and to correspondingly rotate the vent fans to tend to force the movement of air thru the vent, an intake aperture entering the jacket at the bottom and a discharge aperture communicating with the top thereof.

9. In a fireplace of the circulator type a firebox having a flue extending upwardly, an air

heating jacket extending about said firebox including an upwardly projecting vent extending over the top of said firebox and alongside said flue, an intake aperture entering the jacket at the bottom and a discharge aperture communicating with the top thereof, said discharge aper-

ture substantially overlying the full width of the firebox, and a curved heat reflector element arranged in said jacket spaced from but facing said firebox, said reflector extending into and overlying said vent.

PAUL H. SROAT.
